CLAIM

The ornamental design for a leak detection water puddle probe, as shown and described.

DESCRIPTION

FIG. 1 is a perspective view of a leak detection water puddle probe, showing my new design in an extended double roller configuration;

FIG. 2 is a top plan view of FIG. 1;

FIG. 3 is a bottom plan view of FIG. 1;

FIG. 4 is a front elevational view of FIG. 1;

FIG. 5 is a rear elevational view of FIG. 1;

FIG. 6 is a left-side elevational view of FIG. 1;

FIG. 7 is a rear elevational view of FIG. 1;

FIG. 8 is an exploded perspective view of FIG. 1;

FIG. 9 is a perspective view thereof, illustrated in a collapsed configuration;

FIG. 10 is a top plan view of FIG. 9;

FIG. 11 is a bottom plan view of FIG. 9;

FIG. 12 is a front elevational view of FIG. 9;

FIG. 13 is a rear elevational view of FIG. 9;

FIG. 14 is a right-side elevational view of FIG. 9;

FIG. 15 is a left-side elevational view of FIG. 9; and,

FIG. 16 is an exploded perspective view thereof, illustrated in a single roller configuration with an additional roller exploded away therefrom.

The broken lines in the drawings are included for the purpose of illustrating portions of the Leak Detection Water Puddle Probe that form no part of the claimed design.
